UNITED STATES PATENT OFFICE.

JOSEPH O. LUTHY, OF SAN ANTONIO, TEXAS.

MELTING POT.

Application filed December 7, 1925. Serial No. 73,803.

The invention relates to a novel form of melting pot primarily adapted for melting relatively soft metal scrap, such as grids of old secondary battery plates and the like, and comprises a central bowl surrounded by a shelf extending from and inclined toward the periphery of the bowl, upon which the scrap is deposited, so that the initial fusion takes place on the shelf and the molten metal runs into the bowl, leaving the dross on the shelf whence it may be readily removed. To facilitate the heating of the shelf, the latter preferably is surrounded by a pendant skirt or apron, which causes the flame from the burner disposed below the bowl to traverse the under face of the shelf before the products of combustion escape under the lower peripheral edge of the apron. The invention also contemplates associating the melting pot with an annular table, upon which it is supported, to provide a drying and preheating chamber between the bowl, the shelf surrounding the bowl and the top of the table, the central opening in the table permitting the flame of the burner to impinge on the bottom of the bowl and traverse the drying chamber adjacent the walls thereof before escaping, the table also having a surface inclined towards its center and having an opening through which any metal which is melted on the table may be discharged into a suitable receptacle.

The invention is illustrated in the accompanying drawings, in which:

Fig. 1 is a perspective view, partly broken away, illustrating a combined melting pot and drying chamber.

Fig. 2 is a similar view showing a simplified form of melting pot.

Referring to Fig. 1 of the drawings, 1 indicates the annular top of a supporting table, which is provided with a peripheral rim 2 and a central flange 3 surrounding the opening in the table. The flanged rim of the table top is provided at intervals with flanged openings 4. The table is supported by legs 6 engaging sockets 5, which latter are formed as integral portions of the top, and the whole is preferably formed of a casting of iron or the like. Preferably the upper surface of the annular table has a slight inclination toward the center, and is provided with a downwardly flared hole or opening 8, adjacent flange 3, to discharge any metal that may be melted on the table.

Mounted on the table-like support is the melting pot and its accessories, which include a central bowl 12 which overlies the flanged opening in the top of the supporting table, the upper edge of the bowl 12 being surrounded by a shelf or flange 11, preferably circular in contour and inclined inwardly from its outer periphery to its line of juncture with the bowl, so as to form an inclined platform to receive the scrap or other material to be melted. The outer periphery of the shelf 11 is provided with an upstanding flange 10, which is interrupted at 17 to provide an opening through which the accumulation of dross or foreign solid material on the shelf may be scraped or otherwise removed. Extending downwardly from the marginal flange 10 are legs 13, adapted to engage the upper edge of the flange 2 on the supporting table 1, and to be held in position by upstanding lugs 7 formed integrally with the said flange 2. It will be noted that, when the melting pot, including the central bowl and the surrounding shelf, is supported on the table-like element, a relatively large space is provided between the top of the table 1 and the shelf 11 of the melting pot, which space is utilized as a chamber or compartment for drying and preliminarily heating scrap or other material to be subsequently melted, and also, under certain conditions, in which the metal of the scrap may be melted in whole or in part, the molten metal discharging through flared opening 8 into a suitable receptacle, from which it may be transferred to the pot 12 or to shelf 11. In order to properly enclose said chamber, the spaces between the legs 13 of the melting pot are closed by panel-like elements 14, which are suspended from the marginal flange 10 of the shelf 11 by hooks 15, so that the panel-like members may be readily removed and replaced. It will be particularly noted that the elements 14 constitute a pendant apron or skirting surrounding the pot and shelf and serve to prevent the products of combustion escaping over the peripheral edge of the table and cause the products to pass down the inner walls of the skirting, thereby enhancing and increasing the heating effect. Obviously instead of employing the panel-like elements for closing the space between the shelf 11 and the table top 1, the shelf 11 may be provided with an integral pendant rim or

apron which will support the shelf and pot, the rim being provided with a suitable opening to give access to the heating chamber.

The annular top 1 of the supporting table 5 may be used without covering but if scrap battery plates containing sulphur or sulphuric acid are to be dried thereon it is preferably covered by sheet asbestos or other acid and heat resisting material to prevent 10 such battery scrap coming in contact with metal. This asbestos covering can be treated with an application of silicate of soda to make the surface more durable.

Disposed below the central opening in the 15 top of table 1 is a burner 20 of any suitable type, which directs the heating flame through a central opening in the table top and against the bottom of the bowl 12, the flame and the products of combustion resulting therefrom being then diverted along the 20 sides of the bowl and against the under surface of the shelf 11, thence downwardly along the side walls of the preheating and drying chamber and ultimately escaping 25 through the openings 4.

In operating this particular form of the apparatus, if the scrap requires a preliminary drying, as would be the case if it included the grids of old secondary battery plates, it is preferably placed on the top of the table or support 1, through the opening formed by removing one of the panels 14, so that the products of combustion from the burner will pass over the scrap, as they traverse 30 the walls of the drying chamber. The scrap to be melted is placed upon the shelf 11, which is heated by direct contact with the flame from the burner or the products of combustion, so that the scrap is melted 35 and the molten metal runs down the inclined surface of the shelf 11 into the central bowl 12, the metal being maintained in a highly fluid condition by the flame from the burner which impinges directly on the bottom 40 of the bowl. As the fusible material of the scrap is melted and runs down into the bowl, the infusible elements thereof, such as the oxide coatings and solid impurities, are left upon the upper surface of the shelf 45 whence they may be scraped off or discharged through the opening 17 in the flange surrounding the shelf. Likewise any dross or skimmings from the metal in pot 12 may be placed on shelf 11 so that the metal taken off with the skimmings will drain back 50 into the pot. It will be particularly noted that a very large proportion of the heat available from the flame supplied by the burner is utilized in drying and preliminarily heating the scrap and in melting the latter and that the bulk of the molten metal of the scrap is delivered into the central bowl with comparatively little contaminating dross or foreign material. It will also be 55 observed that the scrap, which is prelimi-

narily treated in the drying chamber or compartment, when brought to proper condition by the heat treatment therein, is removed from said chamber and placed on the shelf 11 of the melting pot, so that the time required to melt the metallic constituents of the scrap is reduced to the minimum.

In the modification shown in Fig. 2, the central bowl 12' is surrounded by the inclined annular shelf 11', as in Fig. 1, the peripheral edge of the shelf being provided with a skirting 10', which forms an upstanding flange above the surface of the table and a pendant apron below the table, the latter having legs 6 secured thereto, by 60 means of which the melting pot is supported in proper elevated position above the central burner 20, the flame from which impinges on the bottom of the bowl 12', is thence deflected along the under surface of 65 the shelf 11', then passes down the inner walls of the skirting 10', and finally escapes under the lower edge of said skirting. In the particular embodiment of the invention, no drying or preheating chamber is provided, but the scrap, or other soft metal to be melted, is placed directly upon the inclined table 11', from which the molten metal runs directly into the bowl 12', leaving the dross on the surface of the table 70 whence it may be scraped and discharged through the lateral opening 17' in the flange surrounding the shelf.

What I claim is:

1. A melting pot comprising a central 100 bowl, a shelf surrounding, extending from and inclined toward the periphery of the bowl to support the material being melted, means for supporting the shelf and bowl, and a burner disposed below the bowl.

2. A melting pot comprising a central bowl, a shelf surrounding, extending from and inclined toward the periphery of the bowl to support the material being melted, a pendant apron surrounding the shelf, and a 105 burner disposed below the bowl.

3. A melting pot comprising a central bowl, an annular shelf extending from and inclined toward the periphery of the bowl to support the material being melted, a pendant apron surrounding the shelf, and a 110 burner disposed below the bowl.

4. A melting pot comprising a central bowl, an annular shelf extending from and inclined toward the periphery of the bowl 115 to support the material being melted, a rim and pendant apron surrounding the shelf, and a burner disposed below the bowl.

5. A melting pot comprising a central bowl, an annular shelf extending from and inclined toward the periphery of the bowl to support the material being melted, an annular base, means for supporting the shelf and bowl in spaced relation upon the base 125 to form a heating chamber between the bowl 130

and shelf and the base, and a burner for directing a flame through the central opening in the base against the bottom of the bowl.

6. A melting pot comprising a central bowl, an annular shelf extending from and inclined toward the periphery of the bowl, legs extending from said shelf, an annular base upon which the bowl and shelf are supported by the legs to form a heating chamber below the bowl and shelf, removable panels closing the space between the legs, and a burner for directing a flame through the central opening in the base against the bottom of the bowl.

15. 7. A melting pot comprising a central bowl, an annular shelf extending from and inclined toward the periphery of the bowl, a rim surrounding the shelf, legs extending from said shelf, an annular base upon which the bowl and shelf are supported by the legs to form a heating chamber below the bowl and shelf, removable panels closing the space between the legs, hooks on the panels engaging the rim of the shelf, and a burner for directing a flame through the central opening in the base against the bottom of the bowl.

25. 8. A melting pot comprising a central bowl, an annular shelf extending from and inclined toward the periphery of the bowl, an annular base, means for supporting the

shelf and bowl in spaced relation upon the base to form a heating chamber between the bowl and shelf and the base, a covering of acid and heat resisting material on said base, 35 and a burner for directing a flame through the central opening in the base against the bottom of the bowl.

9. A melting pot comprising a central bowl, an annular shelf extending from and inclined toward the periphery of the bowl, a rim surrounding the shelf, legs extending from said shelf, an annular base covered with acid and heat resisting material upon which the bowl and shelf are supported by 40 the legs to form a heating chamber below the bowl and shelf, removable panels closing the space between the legs, hooks on the panels engaging the rim of the shelf, and a burner for directing a flame through the central 50 opening in the base against the bottom of the bowl.

10. A melting pot comprising a central bowl, a shelf extending from and inclined toward the periphery of the bowl to support the material being melted, a burner disposed below the bowl, and a support below the bowl and adjacent the burner to receive material to be dried by the products of combustion from the burner.

In testimony whereof I affix my signature.
JOSEPH O. LUTHY.
